(57) **CLAIM**

The ornamental design for an earbud headphone case as shown and described.

DESCRIPTION

FIG. 1 is a perspective view of an earbud headphone case showing the new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in FIGS. 1-7 illustrate features of the earbud headphone case that do not form any part of the claimed design.

1 Claim, 4 Drawing Sheets
